(57) **CLAIM**

The ornamental design for a garden hose reel cover, as shown and described.

DESCRIPTION

FIG. 1 is a front, right, and top perspective view of a garden hose reel cover, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of an area **8** circumscribed in FIG. 1 showing the drawstring part of the garden hose reel cover.

The evenly spaced broken lines in the drawings depict portions of the garden hose reel cover that form no part of the claimed design. The dot dash broken lines in FIGS. 1 and **8** denote the boundary of the detail view area and form no part of the claimed design.
